UNITED STATES PATENT OFFICE.

ALBERT SCHEIBLE, OF CHICAGO, ILLINOIS, ASSIGNOR TO JUNIATA STAFFORD, OF CHICAGO, ILLINOIS.

ANCHORING DEVICE.

No. 909,947.

Specification of Letters Patent.

Patented Jan. 19, 1909.

Application filed March 6, 1907. Serial No. 360,943.

To all whom it may concern:

Be it known that I, ALBERT SCHEIBLE, a citizen of the United States, residing at Chicago, in the county of Cook and State of Illinois, have invented a certain new and useful Improvement in Anchoring Devices, of which the following is a full, clear, concise, and exact description, reference being had to the accompanying drawings, forming a part of this specification.

My invention relates to anchoring devices, and has for its object the simplified formation of these devices which at the same time will be very effective in use.

My invention will be fully explained by reference to the accompanying drawing, showing one embodiment thereof, and will be pointed out in the claims.

The drawing shows the preferred embodiment of the invention and the manner of the use of devices made in accordance therewith, in which drawing—

Figure 1 is a view illustrating a device as it is about to be inserted through a wall portion. Fig. 2 is a view similar to Fig. 1, with the exception that the device has been projected through an opening in the wall portion, an end of the wall portion being more fully indicated than in Fig. 1. Fig. 3 is a view similar to Fig. 2, with the exception that the anchor bolt structure has been rotated a half revolution so that the inner portion of the anchor bolt structure will assume the position illustrated. Fig. 4 is a view in the direction of arrow 4, Fig. 3.

Like parts are indicated by similar characters of reference throughout the different figures.

The device of my invention is adapted particularly for use in connection with wall portions (the term "wall" being intended to include in its definition, ceilings or any supporting body with which the device of my invention may be used) that are not readily adapted to have threaded engagement with bolts or screws. Such a wall portion is indicated at *a* in each of the figures and may, for the sake of explanation, be assumed to be of hollow tiling, as indicated in Fig. 2. This tiling is shown as provided with a hole *b* therethrough, of a size sufficient to admit the passage of the anchor element *c* therethrough when said anchor element occupies the position shown in Fig. 1. The said anchor element is formed of strip

metal bent into U-shape, the plane of the U being parallel with the direction of thrust of the anchor element as it is being passed through the wall. By the expression "plane of the U" I mean that plane with respect to which the broad surfaces of the anchor element as viewed in Figs. 1, 2 and 3, are perpendicular, and which plane is parallel with the long edges of the anchor element, clearly shown in Fig. 4. In other words, the plane of the U is parallel with the plane that contains the long edges of the U, appearing most clearly in Fig. 4.

Apertures *d* are formed in the limbs of the U-shaped anchor element, preferably practically half way between the ends of the U and preferably practically half way between the long edges of the strip metal forming the anchor element. A union *e* (in the embodiment of the invention shown, this union being a nut) is desirably provided with trunnion projections *f* that are inserted within the apertures *d*. In order to permit of this assembly of the nut and anchor element, the limbs of the anchor element are spread apart sufficiently to permit of the alinement of the ears *f* with the apertures *d*, whereafter said limbs are approached until the said ears *f* are sufficiently projected through the said apertures. I desirably employ distance preserving means to prevent the limbs from becoming separated after they have been thus approached, which distance preserving means desirably resides in a pin *g* having a head *g*¹ at one end engaging one limb of the anchor element and having its other end bent over at *g*² to engage the other limb of the anchor element. The pin *g* prevents the limbs from spreading and the nut *e* prevents the limbs from collapsing. A shaft *h* is coupled with the anchor element. In the embodiment of the invention shown this shaft *h* is the threaded shank of a bolt having threaded connection with the nut *e* which constitutes the union between the bolt shank and the anchor element.

When the structure is to be passed through a wall portion, the parts are first positioned as indicated in Fig. 1 (assuming that the wall portion is vertical), in which position of the parts some suitable structural feature is provided upon the anchor element that will prevent the anchor element from rotating any further in a counter-clockwise di-

rection (with the parts positioned as shown in Fig. 1). This structural feature may, if desired, also reside in the pin *g*, which is caused to rest against the shank *h*, since the 5 portion of the anchor element to the left of the trunnions *f* is heavier than the portion of said anchor element to the right of said trunnions, this additional weight being preferably afforded by the metal in the curved 10 end *i* of the anchor element, the pin *g* not being of sufficient weight to equal the additional weight supplied at *i*. While I prefer to provide the preponderating weight at the 15 bend of the U, I do not wish to be limited to this characteristic. Thus the parts when positioned as indicated in Fig. 1, may be thrust through the aperture *b* as indicated in Fig. 2, whereafter when the shank *h* is turned a half revolution, the anchor element 20 will assume a vertical position, because the preponderating weight at *i* is no longer resisted by the engagement of the pin *g* with the shank *h*, said pin having been disposed above said shank when said shank was 25 turned a half revolution. When the parts are in the position shown in Figs. 1 and 2, the anchor element extends longitudinally of the shaft *h*, the element *g* being so positioned as to permit this disposition of the 30 parts as the anchor element is being thrust through the wall. It is, of course, understood that the nut *e* turns bodily with the shank, in order that the pin *g* may be disposed above the shank to permit the anchor 35 element to assume the position shown in Fig. 3. The shanks *h* may be of suitable formation, whereby they may be adapted to different purposes. They are threaded where united with the anchor element, when it is 40 intended to have the anchor element moved bodily along the same, and when this characteristic is to be provided, the means of attachment between the bolt shank and the anchor element is preferably the threaded 45 nut *e*.

I do not wish to be limited to a construction, however, wherein the anchor element is to be moved bodily along the shaft *h*. The bolt shank, for many purposes, is preferably 50 provided with a head *l* integrally formed therewith, which head may, if desired, have a screw-driver slot. I do not wish to be limited, however, to the presence of a head upon the element *h*.

55 The advantage of my improved construction will be readily apparent to those familiar with this art, since it is known to them that it has been customary hitherto for the user to hold the anchor bar parallel 60 to the shaft when inserting the anchor bar, so as not to have this bar catch on the outside of the wall. It is frequently difficult for the installer to thus hold the anchor element and shaft in parallel relation.

65 Having thus described my invention, I

claim as new and desire to secure by Letters Patent:—

1. A device of the class described comprising an anchor element formed of strip metal bent into U-shape, the plane of the U being substantially parallel with the direction of thrust of the anchor element when being inserted, a shaft, and a nut having trunnions projecting through openings in the sides of the anchor element and having threaded engagement with the shaft, said nut affording pivotal connection between the shaft and anchor element, there being means for limiting the rotation of said anchor element in one direction to enable said anchor element and shaft to be disposed and held longitudinally of each other when said anchor element is to be passed through an opening, the portions of the anchor element upon opposite sides of the pivotal connection thereof with the shaft being of unequal weight, the preponderating weight acting when the parts are in one position, to cause, or tend to cause, the rotation of the anchor element in the aforesaid direction of rotation, the aforesaid limiting means co-acting with this preponderating weight to maintain the anchor element and shaft in substantial alignment during the passage of the anchor element through an opening, said preponderating weight serving to swing the anchoring element at an angle when the shaft and anchoring element are given substantially a half turn about the axis of the shaft.

2. A device of the class described comprising an anchor element formed of strip metal bent into U-shape, the plane of the U being substantially parallel with the direction of thrust of the anchor element when being inserted, a shaft, and a nut having trunnions projecting through openings in the sides of the anchor element and having threaded engagement with the shaft, said nut affording pivotal connection between the shaft and anchor element, there being means for holding the anchor element and shaft in alignment as said anchor element is being passed through an opening.

3. A device of the class described comprising an anchor element formed of strip metal bent into U-shape, the plane of the U being substantially parallel with the direction of thrust of the anchor element when being inserted, a shaft, and a nut having trunnions projecting through openings in the sides of the anchor element and having threaded engagement with the shaft, said nut affording pivotal connection between the shaft and anchor element.

4. A device of the class described comprising an anchor element formed of strip metal bent into U-shape, the plane of the U being substantially parallel with the direction of thrust of the anchor element when being

inserted, and a shaft pivotally connected with the anchor element, there being means for limiting the rotation of said anchor element in one direction to enable said anchor element and shaft to be disposed and held longitudinally of each other when said anchor element is to be passed through an opening, the portions of the anchor element upon opposite sides of the pivotal connection thereof with the shaft being of unequal weight, the preponderating weight acting when the parts are in one position, to cause, or tend to cause, the rotation of the anchor element in the aforesaid direction of rotation, the aforesaid limiting means co-acting with this preponderating weight to main-

tain the anchor element and shaft in substantial alinement during the passage of the anchor element through an opening, said preponderating weight serving to swing the anchoring element at an angle when the shaft and anchoring element are given substantially a half turn about the axis of the shaft. 20

In witness whereof, I hereunto subscribe 25 my name this 27th day of February A. D., 1907.

ALBERT SCHEIBLE.
